INVENTOR.

Thomas Boudren

UNITED STATES PATENT OFFICE.

THOMAS BOUDREN, OF BRIDGEPORT, CONNECTICUT, ASSIGNOR OF THREE-FOURTHS HIS RIGHT TO THE WHITE MANUFACTURING COMPANY, GEORGE H. JOHNSON, AND CHARLES H. STEVENS, OF SAME PLACE.

IMPROVEMENT IN ADJUSTABLE LAMP-SUPPORTS FOR VEHICLES.

Specification forming part of Letters Patent No. 147,362, dated February 10, 1874; application filed December 13, 1873.

To all whom it may concern:

Be it known that I, THOMAS BOUDREN, of Bridgeport, in the county of Fairfield and in the State of Connecticut, have invented certain new and useful Improvements in Adjustable Lamp-Support for Carriages; and do hereby declare that the following is a full, clear, and exact description thereof, reference being had to the accompanying drawings and to the letters of reference marked thereon, making a part of this specification.

The object of my invention is to furnish a portable, sure, and simple method of applying the use of a lamp to any ordinary buggy or carriage.

Lamps for a similar purpose are at present in use on public and private conveyances; but such lamps are usually placed permanently in position when the carriage is built. My improvement does not relate to this class of carriages, but rather to those in which a lamp or lamps were not a part of the original design of the manufacturer.

Physicians and others who have occasion to drive during the night have long felt the necessity of an improvement of this nature. By my invention they are furnished with a lamp, together with such fixtures or attachments as will enable them to fasten it securely and quickly to the dash-board of their carriage, and as readily detach it in the day-time when they have no occasion for its use.

My improvement consists in providing a bracket or support for a carriage-lamp with a clamp, by which it may be readily and securely attached to the dash-board of a carriage, and as easily removed when not in use. My improvement further consists in providing a support for a carriage-lamp not only with a clamp for the above purpose, but also constructing it with a joint between the clamp which fastens it to the dash-board and the lamp, with an arrangement also for adjusting and clamping the two parts of the support where the joint is formed, so that the lamp may be held at different angles. This adjustable feature of my improvement enables me

to apply it to dash-boards of any shape, and still hold the lamp in an upright position.

In the accompanying drawings forming part of this specification, Figure 1 represents a view in elevation of my improvement as attached to the dash-board of a carriage; Fig. 2, the thumb-nut of the adjustable joint and clamp B; Fig. 3, the disk C, in combination with the arm f of the support, to which the lamp is fastened, and shank d; Fig. 4, a sectional view of disk C and shank d in elevation. Fig. 5 represents the disk D, in combination with the clamp A, which fits over the dash. e is an orifice in the center of the disk D, for receiving the shank d. Figs. 6, 7, 8, 9, 10 represent the parts in detail of the clamp A. Fig. 11 represents an end view in elevation of the adjustable clamp B.

The manner of using my improvement is as follows: The two parts of the clamp A are placed so as to straddle the dash, and securely fastened thereon by the thumb-screw b. To adjust the lamp to an upright position, I have simply to turn the thumb-nut, Fig. 2, to the left, which allows the serrated disks C and D to be separated sufficiently to turn the lamp to any required position. The disks can then be brought together again and fastened, the serrated portions fitting into each other, as shown in Fig. 11, and making a rigid joint. The lamp may be easily detached, if desirable, and used as a lantern, the support or bracket forming a convenient handle.

I usually solder the lamp to the support; but it is obvious it may be fastened in other ways.

Different styles of clamps from those I have described may also be used. The clamp for the dash might be hinged at the top, and have the thumb-screw b pass through the dash.

I do not claim anything, broadly, on the serrated disks C and D, as I am aware that they are used in other combinations, and for other purposes.

I claim as my invention—

The combination, with a carriage-lamp, of

an arm attached to the back of the lamp, and provided with an adjustable joint, B, at or near the middle thereof, and a clamp, A, and screw *b* on the end of the same, all substantially as and for the purposes herein set forth.

In testimony that I claim the foregoing I

have hereunto set my hand this 11th day of December, 1873.

THOMAS BOUDREN.
